(57) **CLAIM**

The ornamental design for a soap dispenser, as shown and described.

DESCRIPTION

FIG. 1 is a perspective view of a soap dispenser showing my new design;

FIG. 2 is another perspective view thereof;

FIG. 3 is a front view thereof;

FIG. 4 is a rear view thereof;

FIG. 5 is side view thereof;

FIG. 6 is another side view thereof;

FIG. 7 is top view thereof; and,

FIG. 8 is a bottom view thereof.

The broken lines show portions of the soap dispenser that form no part of the claimed design.
